UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,276,521.

Specification of Letters Patent. Patented Aug. 20, 1918.

Application filed June 15, 1916. Serial No. 103,854.

To all whom it may concern:

Be it known that I, CHARLES L. GOODRUM, a citizen of the United States, residing at New York, in the county of New York and 5 State of New York, have invented certain new and useful Improvements in Telephone Systems, of which the following is a full, clear, concise, and exact description.

This invention relates to two-wire multiple automatic telephone systems of the character described in Patent No. 1,251,503, granted to me January 1, 1918 and relates particularly to an arrangement for registering the number of telephone conversations 15 which take place on a given telephone line in such a system.

The object of the invention is to provide an arrangement of this character in which the operation of the message register appropriated to a telephone line may be controlled in a simple and reliable manner and without hindrance to the talking currents in the lines.

In accordance with a feature of the invention, a controlling magnet of the message register is normally bridged between a talking conductor of the telephone line to which it is appropriated and the source of power through which the apparatus of the exchange is actuated and so arranged that it will offer no impedance to the talking currents.

The invention will be more fully understood from the following detailed description of the system and the drawings, in which Figure 1 shows the invention applied to a system employing an automatic switch for extending the telephone line to a connecting circuit. Figs. 2 and 3 are modified forms of the invention applied to systems similar to that shown in Fig. 1.

In the modification shown in Fig. 1, the apparatus and circuits are designated by the same reference numerals as used to designate similar apparatus in the application to which reference has been made. The line relay is shown at 1, test relay at 4, cut-off relay at 24, the line finder brushes and terminals at 20, 21, and 20', 21', the side-switch arms at 7, 12, 13 and 14, side-switch magnet at 11, and the motor magnets of the line finder at 9 and 16. It is thought that the invention will be best understood by describing the operation in extending a call and in 55 registering such call, provided it is success-

ful. As the operation of the apparatus for extending the call to the line of the called subscriber is described in detail in the patent above referred to, the operation, with the exception of that part which has to do 60 with the operation of the message register, will not be described in detail, but will be merely outlined.

Assuming that the subscriber shown at the left of Fig. 1 removes his receiver from the hook and initiates a call, line relay 1 will operate, closing a circuit for the relay 2, causing it to operate. In response to the operation of relay 2, a circuit is closed for stepping magnet 9 over the side-switch arm 70 7 in position 1, which causes such magnet to step the brushes around until the test brush 10 encounters a contact 5 that is individual to the group of lines in which the calling line appears in the terminals of the 75 line finder switch.

When contact 10 makes contact with the terminal 5, magnet 11 of the side switch is energized, and the side switch is moved into its second position, in which position the 80 stepping magnet 16 is energized over the back contact of relay 4, and the magnet 11 of the side switch is also energized over a circuit including the relay 3, front contact of relay 2 and back contact of relay 4. The 85 energization of the magnet 11 at this time does not move the side-switch arms, and the side switch remains in position 2.

In response to the operation of the stepping magnet 16, the brushes 20 and 20' move 90 over terminals 21 and 21', until the particular terminals 21 and 21' are reached which are individual to the calling line, when a circuit will be closed from a source of alternating current 18, through the test relay 4, 95 front contact and right-hand armature of line relay 1, upper winding of relay 25, terminal 21, contact 20, side-switch arm 14, in position 2, condenser 22, resistance 23 to ground. The register magnet indicated at 100 25 is provided with two windings which are differentially arranged on the core, the arrangement being such that current through either winding alone will not magnetize the core sufficiently to attract the magnet armature, nor will current in both windings magnetize the core sufficiently unless the current flow in both windings is in such a direction that the magnetic effects produced thereby aid each other.

The circuit just traced includes only the upper winding of the magnet 25, so that the magnet will not be operated at this time. An impulse, however, will pass through the 5 relay 4, causing it to energize and open the circuit of the stepping magnet 16 to stop the line finder switch with the contacts 20, 20', resting on the terminals 21, 21', individual to the calling line. The energization of the 10 relay 4 also opens the circuit previously traced for the side-switch magnet 11, which, in deenergizing, moves the side-switch arms into position 3.

In position 3 of the side switch, a circuit 15 is established for the cut-off relay 24, which may be traced as follows: battery 35, lower winding of the register magnet 25, cut-off relay 24, terminal 21', contact 20', side-switch arm 13 in position 3, resistance 23 to 20 ground. The cut-off relay 24 will operate, but the magnet 25 will not operate, as only the lower winding thereof is energized over this circuit. In response to the actuation of the impulse sender at the calling subscriber's 25 station, the connection may be extended to the contacts of the called subscriber's line by means of automatic switches which are not shown, but which may be of any usual construction, but are preferably of the construction 30 shown in applicant's prior application 35,326. It may be noted that although the impulses for controlling the operation of the selector switches pass through the upper winding of the register 35 magnet 25, while current is also flowing in the lower winding thereof, the register magnet will not operate as the magnetizing effects of the windings under these circumstances are opposed.

40 The operation of testing and ringing takes place in the usual manner and will not be described in detail. When the called subscriber answers, apparatus associated with the selector switches used in establishing a 45 connection will operate, and will connect a source of potential on the upper conductor *a*. This apparatus may be in the form of a relay or an automatic switch, such as a side switch, which operates in response to 50 the act of the calling party answering the call. When battery is connected to conductor *a*, a circuit is established over such conductor by way of side-switch arm 14 in position 3, contact 20, terminal 21, upper winding 55 of register magnet 25, lower armature and front contact of cut-off relay 24 over line 1 to the calling subscriber's substation apparatus, thence by line 2, front contact of upper armature of the cut-off relay to terminal 21', contact 20', side-switch arm 13 in 60 position 3, resistance 23 to ground. Under these conditions, both windings of the register magnet 25 will be energized, and as the polarity of the battery connected to line conductor *a* has been chosen so that the two

windings under these circumstances will assist one another, the register magnet 25 will be energized and will operate a suitable counting train to register the call. When the magnet 25 operates, the armature 70 thereof will close a shunt circuit around the upper winding of such magnet, short-circuiting this winding and shunting it from the talking circuit. The magnet 25, however, will remain operated as the current 75 flowing through the lower or holding winding will be sufficient to hold the armature thereof attracted even though the upper winding is short-circuited. The register magnet 25 will therefore remain energized 80 as long as the connection is established, and the subsequent operation of the switchhook by the calling subscriber at any time while the connection is established will not affect the registration of the call. 85

The modification shown in Fig. 2 differs from that shown in Fig. 1 in that the register magnet itself is not included in the talking conductor, but is controlled by a polarized relay indicated at 30, which is included 90 in one of the talking conductors and which is adapted to be shunted out of the talking conductor by the operation of the register magnet 25.

The operation of the line finder is identically the same as in the modification shown in Fig. 1, and will not be described. Therefore, it will be assumed that the line finder has found the terminals of the calling line and that the side-switch arms 13 and 14 are 100 in position 3, in which position a circuit is closed from battery 35, left-hand winding of register magnet 25, cut-off relay 24, polarized relay 30, contacts 21' and 20', side-switch arm 13, resistance 23 to ground. The 105 cut-off relay will be energized, but the magnet 25 will not be energized, as current is flowing through only one winding thereof, and the polarized relay 30 will not be energized due to the polarity of the current flowing therethrough. However, as soon as the call is extended to the calling subscriber and said calling subscriber answers, means associated with the selector switches employed in establishing the connection is rendered operative, and connects a source of potential of the proper polarity to operate the polarized relay 30 over the conductor *a*. A circuit will therefore be established from such source of potential through the conductor *a*, arm 14, contact 20, terminal 21, front contact and upper armature of cut-off relay 24, conductor 1 to the subscriber's substation to conductor 2 and lower armature and front contact of cut-off relay 24, 115 polarized relay 30, terminal 21', contact 20', arm 13, resistance 23 to ground. 120

A current impulse of the polarity required to operate the polarized relay will pass over the circuit just traced and hence through 130

- the winding of the polarized relay 30, which will operate. The operation of the polarized relay 30 closes a circuit from battery 35 to the right-hand winding of the magnet 25, 5 through the armature of polarized relay 30 to ground. Both windings of the magnet 25 are now energized, and, due to their arrangement on the core, their effect will be cumulative so that the magnet 25 will be 10 energized, and, in attracting its armature, will close at its front contact a shunt around the polarized relay 30, thus shunting such relay 30 from the talking circuit. Upon the deenergization of the relay 30, due to its 15 shunting by the magnet 25, the magnet 25 will still hold its armature in its attracted position, due to the fact that the circuit through the left-hand winding thereof is still established, and the energization of 20 such winding is sufficient to hold the armature, once it has been attracted.
- In the modification shown in Fig. 3, the apparatus individual to the line and the line finder switch is arranged identically as in 25 the modification shown in Fig. 1, with the exception that the side-switch magnet 11 is provided with an armature and contact for a purpose which will hereinafter appear. In this modification, the register magnet is 30 not provided with a separate holding winding. A polarized relay 30 is also employed, but in this case it is not connected at any time in the talking circuit. In this modification, as in Fig. 1, the line finder operates, 35 and when the terminal 21' and contact 20' are brought into connection, the side-switch arms 14, 13, 12 and 7 are moved to position 3. In position 3 of the side switch, a circuit is established from the battery 35, through 40 the register magnet 25', cut-off relay 24, terminal 21', contact 20', side-switch arm 13 in position 3, resistance 23 to ground. The cut-off relay 24 will be energized over this circuit, but the resistance 23 is so adjusted 45 that there will not be sufficient current flowing in the circuit to operate the register magnet 25'. However, when the connection has been established and the called subscriber answers, a source of potential of the 50 polarity required to operate the polarized relay 30 will be placed upon the conductor *a* by apparatus associated with the selector switches used in establishing the connection. A circuit may therefore be traced from such 55 source of potential through the conductor *a*, polarized relay 30, side-switch arm 14, position 3, contact 20, terminal 21, lower armature and front contact of cut-off relay 24, conductor 1, subscriber's station, conductor 2, upper armature and front contact 60 of relay 24, terminal 21', contact 20', side-switch arm 13, position 3, resistance 23 to ground. The operation of the polarized relay shunts the resistance 23 from the energizing circuit of the magnet 25', in series 65 with the cut-off relay 24, previously traced, so that the energizing circuit for the register magnet 25', may now be traced as follows: battery 35, register magnet 25', cut-off relay 24, terminal 21', contact 20', side-switch arm 13, position 3, side-switch arm 6, position 3, armature of polarized relay 30 to ground. 70
- A circuit is also closed for the magnet 11 of the side-switch which may be traced from battery, magnet 11, side-switch arm 12 in 75 position 3, armature and back contact of relay 11, side-switch arm 6, position 3, armature and contact of polarized relay 30. The magnet 11 will energize, and in energizing break its energizing circuit, and as a result 80 of this operation the side switch will be moved into position 4, which is the through or talking position.
- Although in position 4 the shunt to ground about the resistance 23 is removed at the 85 arm 6, there will still be sufficient current flowing through the magnet 25' to maintain its armature attracted so that the register magnet 25' will remain energized until disconnect takes place. 90
- What is claimed is:
1. In a telephone system, a telephone line, a message register for recording calls on said line, an electromagnet for controlling the operation of said register, a cut-off relay, means for operating said electromagnet independent of said cut-off relay, and a series holding circuit for said electromagnet and said cut-off relay. 95
  2. In a telephone system, a telephone line, a message register for recording calls on said line, a pair of electromagnet coils for controlling said register, and circuits for said coils, one extending through the contact of said cut-off relay and the other through the 100 winding of said cut-off relay.
  3. In a telephone system, a telephone line, a message register for recording calls on such line, an electromagnet for controlling the operation of said register, an automatic 110 switch provided with a pair of brushes for extending said calling line to a connecting circuit, and an energizing and holding circuit for such electromagnet including one of such pairs of brushes. 115
  4. In a telephone system, a telephone line, a message register for recording calls on said line, an electromagnet for controlling the operation of said register, an automatic switch provided with brushes for extending 120 said calling line to a connecting circuit, a cut-off relay, and a series holding circuit for said magnet and said relay extending through one of said switch brushes in the talking circuit. 125
  5. In a telephone exchange system, a plurality of subscribers' lines, cut-off relays therefor, a finder switch having fixed contacts in which said subscribers' lines terminate, a connecting circuit terminating in the 130

- movable contacts of said switch, a message register for each of a plurality of subscribers' lines, an electromagnet for each of said message registers for controlling the operation thereof, said electromagnet having its winding in series with the winding of its associated cut-off relay, and means in said connecting circuit for controlling the operation of said electromagnet.
10. 6. In a telephone exchange system, a plurality of subscribers' lines, cut-off relays therefor, a finder switch having fixed contacts in which said subscribers' lines terminate, a connecting circuit terminating in the movable contacts of said finder switch a message register for each of a plurality of subscribers' lines, an electromagnet for each of said message registers for controlling the operation thereof, said electromagnet having its winding in series with the winding of its associated cut-off relay, electromagnetic means in said connecting circuit for causing said electromagnet to operate when a called subscriber answers, and means for retaining said electromagnet energized until disconnection takes place.
7. In a two-wire multiple telephone exchange, a telephone line, a source of current, a cut-off relay and a message register bridged between a talking conductor of said line and said source of current, and means for operating said message register independently of said cut-off relay.
8. In a two-wire multiple telephone exchange, a telephone line comprising two talking conductors, a source of current for actuating the apparatus of said exchange, a cut-off relay and a message register bridged between a talking conductor of said line and said source of current, and means for operating said message register independently of said cut-off relay.
9. In a telephone system, the combination with a telephone line, automatic switches for extending said line and a source of electrical energy for actuating said switches, of a message register bridged between a talking conductor of said line and said source, and means controllable over said line for actuating said register.
10. In a telephone system, the combination with a telephone line, automatic switches provided with two brushes and a two-wire multiple bank of terminals with which said brushes coöperate for extending said line and a source of electrical energy for actuating said switches, of a message register for recording the number of times said line is extended, said register being bridged between said source and a talking conductor of said line and controllable over said line.
11. In a telephone system, a telephone line, a trunk line, means for extending said line to said trunk line, a source of electrical energy, a message register bridged between a talking conductor of said telephone line and said source, and means in said trunk line for causing the actuation of said register.
12. In a telephone system, a telephone line comprising two talking conductors, a source of electrical energy, means for extending said line, a message register bridged between one of said talking conductors and said source, and means independent of the talking current in said line for operating said register.
13. In a telephone system, a telephone line comprising two talking conductors, a source of electrical energy, means for extending said line, a message register bridged between one of said talking conductors and said source, and means for actuating said register subsequent to the extension of said line.
14. In a telephone system, a telephone line comprising two talking conductors, a trunk line, a source of electrical energy, means for extending said line to said trunk line, a message register bridged between one of said talking conductors and said source, and means independent of the talking current in said line included in said trunk line for operating said register.
15. In a telephone system, a telephone line comprising two talking conductors, a trunk line, a source of electrical energy, means for extending said line, a message register bridged between one of said talking conductors and said source, and means included in said trunk line for actuating said register subsequent to the extension of said line. 100
16. In a telephone system, telephone lines each comprising two talking conductors, a source of electrical energy common to said lines, means common to said lines for extending said lines, a message register individual to each of said lines bridged between a talking conductor of the associated line and said source, and means common to said lines for causing the actuation of said message registers. 105
- In witness whereof, I hereunto subscribe my name this 14th day of June A. D. 1916. 110
- CHARLES L. GOODRUM.
